US0D1017414S

(12) United States Design Patent (10) Patent No.: US D1,017,414 S
(45) Date of Patent: * Mar. 12, 2024

(54) POWDER COMPACT

(71) Applicant: LVMH FRAGRANCE BRANDS,
Levallois-Perret (FR)

(72) Inventor: Romain Spitzer, Levallois-Perret (FR)

(73) Assignee: LVMH FRAGRANCE BRANDS,
Levallois-Perret (FR)

() Term: 15 Years

(21) Appl. No.: 35/514,675

(22) Filed: May 23, 2022

(80) Hague Agreement Data

Int. Filing Date: May 23, 2022

Int. Reg. No.: DM/221674

Int. Reg. Date: May 23, 2022

Int. Reg. Pub. Date: Jul. 8, 2022

(30) Foreign Application Priority Data

May 20, 2022 (WO) WIPO117725

(51) LOC (14) Cl. 09-01

(52) U.S. Cl.

USPC D9/558
